US00D688543S

(12) **United States Design Patent**
Neitzell et al.

(10) **Patent No.:** US D688,543 S
(45) **Date of Patent:** ** Aug. 27, 2013

(54) **SAW BLADE**

(71) Applicant: **Milwaukee Electric Tool Corporation**,
Brookfield, WI (US)

(72) Inventors: **Roger D. Neitzell**, Palmyra, WI (US);
Ryan J. Malloy, Milwaukee, WI (US);
Austin Kazda, Wauwatosa, WI (US);
Robert W. Butzen, Colgate, WI (US)

(73) Assignee: **Milwaukee Electric Tool Corporation**,
Brookfield, WI (US)

(**) Term: **14 Years**

(21) Appl. No.: **29/433,586**

(22) Filed: **Oct. 2, 2012**

Related U.S. Application Data

(63) Continuation-in-part of application No. 29/416,281,
filed on Mar. 20, 2012, and a continuation-in-part of
application No. 13/566,985, filed on Aug. 3, 2012.

LLP

(57) **CLAIM**

We claim the ornamental design for a saw blade, as shown and
described.

DESCRIPTION

FIG. 1 is a perspective view of a saw blade according to a first
embodiment of the invention;

FIG. 2 is an opposite side perspective view thereof;

FIG. 3 is a side view thereof;

FIG. 4 is an opposite side view thereof;

FIG. 5 is a top view thereof;

FIG. 6 is a bottom view thereof;

FIG. 7 is an end view thereof, shown at an enlarged scale;

FIG. 8 is an opposite end view thereof, shown at an enlarged
scale;

FIG. 9 is a perspective view of a saw blade according to a
second embodiment of the invention;

FIG. 10 is an opposite side perspective view thereof;

FIG. 11 is a side view thereof;

FIG. 12 is an opposite side view thereof;

FIG. 13 is a top plan view thereof;

FIG. 14 is a bottom plan view thereof;

FIG. 15 is an end view thereof, shown at an enlarged scale;
and,

FIG. 16 is an opposite end view thereof, shown at an enlarged
scale.
